(57) **CLAIM**

The ornamental design for fit-over sunglasses, as shown and described.

DESCRIPTION

FIG. 1 is a perspective view of a pair of fit-over sunglasses showing my new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The application relates to the design of a pair of sunglasses with broad lenses, a square corner at the edge of each lens, and a square upper portion above the lenses.
